(57) **CLAIM**

The ornamental design for a bottle cap with ribs and rib projections, as shown and described.

DESCRIPTION

FIG. 1 is a perspective view of a first embodiment of the bottle cap.

FIG. 2 is a front view of the first embodiment of the bottle cap.

FIG. 3 is a back view of the first embodiment of the bottle cap.

FIG. 4 is a top plan view of the first embodiment of the bottle cap.

FIG. 5 is a bottom view of the first embodiment of the bottle cap.

FIG. 6 is a perspective view of a second embodiment of the bottle cap.

FIG. 7 is a front view of the second embodiment of the bottle cap.

FIG. 8 is a back view of the second embodiment of the bottle cap; and,

FIG. 9 is a top plan view of the second embodiment of the bottle cap, the bottom plan view having the appearance of FIG. 5.

The broken lines in FIG. 1 represent unclaimed environmental subject matter and form no part of the claim; the broken line in FIG. 6 depicts the claim boundary and forms no part of the claim.
